CHILD'S SEAT FOR BARBER CHAIR

Arnold A. Mason and Russell F. Mason,
Lake View, Iowa

Application October 2, 1931. Serial No. 566,478

1 Claim. (Cl. 155—132)

This invention presents an improved child's seat for barbers' chairs.

The main object of the invention is to provide a simple and readily operated seat which may be elevated to any desired height above the seat of the barber's chair and which will afford a convenient and comfortable seat for a child.

Another object is to provide an arrangement whereby a rear and central section of the chair 10 seat itself may be raised or lowered independently thereof to act as the child's seat.

With these and other objects in view the invention resides in the novel construction and arrangement of parts as hereinafter set forth and 15 claimed, reference being had to the accompanying drawing wherein:

Figure 1 is a side view of a barber's chair showing the child's seat raised for use.

Figure 2 is a plan view of the chair seat showing the position of the section which serves as the child's seat.

Figure 3 is an enlarged rear view of the chair seat showing the child's seat and the device for raising and lowering the same.

25 Referring now more particularly to the drawing the reference character A designates a barber's chair of conventional form including a seat B, arms C, back D and supporting stand E in which the usual hydraulic jack or lift (not shown) is arranged for raising and lowering the chair.

In accordance with the present invention the seat B is provided with a U-shaped cut out or recess 1 in its rear edge, as shown, the said cut 35 out terminating at its lateral margins a considerable distance inwardly from the sides of the chair seat B. In this cut out is disposed the child's seat 2 which corresponds in thickness and general construction with the seat B whereby it 40 will serve as a part of that seat B when not in use. A U-shaped bracket 3 is hung from the rear edge of the chair seat B by bolts 4 passed through the out turned ends 5 of its legs 6 into the underside of the seat B and a hydraulic jack 45 or lift 7 of conventional form is mounted on the horizontally disposed bight 8 of this bracket beneath the child's seat 2. A base plate 9 is secured to the underside of the child's seat 2 and a plunger shaft 10 is depended from this plate 50 down into the jack cylinder 11 of the jack 7 where it is provided with a piston (not shown) in conventional manner. The jack 7 has also a pump cylinder 13 in which is located a piston (not shown) operable by a handle 14 whereby an upward pressure may be exerted in the jack cylin-

der 11 to raise the plunger shaft 10. It is obvious that a screw type or similar jack may be employed in lieu of the hydraulic jack if desired.

In use and when it is desired to elevate the child's seat 2, the handle 14 is raised and lowered causing the shaft 10 to raise in the jack cylinder 11 until the seat has been elevated to the desired height. When not in use the child's seat 2 is lowered to the level of the chair seat B by releasing the pressure in the jack cylinder 11 65 by any suitable release valve (not shown). It will thus be evident that a seat of convenient, simple and comfortable form is provided.

While we have herein set forth a certain preferred embodiment of our invention it is understood that we may vary from the same in minor structural details so as best to construct a practical device for the purpose intended, not departing from the spirit of the invention and within the scope of the appended claim. 75

We claim:

In a device of the kind described for a barber chair having a seat with a U-shaped recess cut out centrally in its rear margin, and there being a child's seat movably mounted in the said recess, the addition of a U-shaped bracket of substantial width secured by its legs to the underside of the chair seat immediately below the said recess, and a hydraulic lift mechanism mounted on the bight of the bracket and connected with the child's seat for raising and lowering same, the point of connection being rearwardly of the center of the child's seat so as to throw the lift mechanism rearwardly for easy access, the bracket being sufficiently wide to form a stable 85 support for the mechanism in its upright position. 90
